Augustus E. Alden, of Providence, R. I.
 Letters Patent No. 2083-Dated June 13-1865.
 Design for a Photographic Card.

The schedule referred to in these Letters Patent and making part of the same.

Swallow to whom these Presents shall come:

Bentham & Hatch, Augustus E. Alden of Providence for the County of Providence and State of Rhode Island, have produced and original design for card photography, and do hereby declare that the said and design is fully described and represented in the following specification and accompanying plate of drawings to which references hereinafter are made.

The figures of the accompanying plate of drawings represent my new design. Fig. 1 is a view of a card photograph showing my design. Fig. 2 is a central horizontal section through the same.

My new design consists of two oval medallions a. a. surrounded by embossed borders, the outer and inner edges b. b. and c. c. of which are beaded, and in the spaces d. d. between the inner edges b. b. and c. c. raised stars e. e. are placed at equal intervals from each other. The beaded rims c. c. being raised from the surface of the card f. f. sunken panels g. g. are formed for containing the pictures. The medallions a. a. are surmounted by an eagle h. h. resting upon a scroll i. i. placed at the top of the medallions in the centre, between them, from underneath this scroll spring the staves k. k. of two American flags l. l. which cross each other and extend in an oblique direction on each side of the eagle h. h. the flags l. l. falling behind the top of each one. d. d. In the centre at the bottom of the medallions a. a. is an American shield m. m. with stars and stripes. Above this shield m. m. are knotted the ends of urns n. n. which extend

around the bottom of each medallion.

DES. 2083

Having thus described my new design of seal I state
my claim as follows:

What I claim as my invention or production and
desire to have secured to me by Letters Patent is

The new design for and photograph of a seal
here described and represented in the drawings.
